ABSTRACT OF THE DISCLOSURE

It is disclosed that olefin sulfonates obtained by saponifying the reaction product of SO_3 and olefins having from about 12 to about 16 carbon atoms per molecule provide excellent hard water detergent materials when the olefins are predominantly unbranched acyclic terminal monoolefins in admixture with from about 3 to about 30 mol percent of beta-branched terminal olefins and from about 3 to about 12 mol percent of internal olefins. Preferred olefin sulfonates are the sodium and potassium salts of alkene sulfonic acids and of hydroxy alkane sulfonic acids. The mixtures of the present invention involve sulfonates with from about 64 to about 97 percent C_{16} , from zero to about 15 percent C_{14} and from about 3 to about 33 percent C_{12} carbon atoms per molecule, in percent by weight.

BACKGROUND OF THE INVENTION

Field of the invention

The invention relates to olefin sulfonates and in particular to synergistic compositions based upon mixtures of olefins of selected molecular weights and selected carbon structural molecular configurations. Preferred olefin sulfonates have useful properties as detergents for washing fabrics, skin, etc. either in the form as produced or in admixture with other detergent actives and adjuvants, and as liquid, powder, flakes, bars, pastes, and the like.

Description of the prior art

Alpha olefin sulfonates are well known in the prior art as being readily produced by the reaction of alpha olefins with SO_3 or with compounds or complexes containing or yielding SO_3 . Of particular interest is the reaction with uncomplexed SO_3 . The reaction is followed by saponification with a caustic or alkaline substance such as a hydroxide, oxide or carbonate of the alkali or alkaline earth metals, such as NaOH and KOH , to produce water soluble metal salts. These products have useful properties for various washing purposes such as cleansing fabrics, skin and dishes. The carbon skeletal structures of the sulfonates are basically isomeric unsaturated and hydroxy saturated isomers having carbon skeletons similar to the starting olefins. Typically, $\text{RCH}_2\text{CH}_2\text{CH}_2\text{CH}=\text{CH}_2$ reacts starting olefins. Typically, $\text{RCH}_2\text{CH}_2\text{CH}_2\text{CH}=\text{CH}_2$ reacted with SO_3 produces predominantly compounds of the formulas:

The prior art teaches generally that such sulfonates can be produced on a basis of olefins of various carbon skeletal configurations having 10 to 24, more or less, car-

2

bon atoms per molecule. For the most part, the prior art preference is for the use of olefins having a single molecular structural configuration, particularly straight chain olefins of the alpha type and for olefins that have 16 or more, preferably 18 or more, carbon atoms per molecule. Thus in the prior art, R of the foregoing formulae is generally a straight chain saturated alkyl group having 5 to 19, more or less, carbon atoms, particularly 11 or more, preferably 13. In some instances olefins have been used that were different from such straight chain olefins. The plurally branched propylene tetramer, for example, has been mentioned. Internal olefins and vinylidene olefins, individually, have been mentioned in a general way but for the most part there is no teaching of synergism in sulfonate mixtures based on mixed olefins.

SUMMARY OF THE INVENTION

The present invention provides synergistic compositions of olefin sulfonates of certain mixed structures and of a specific narrow range of molecular weights, expressed as a specific area on the proportions plot of the figure which have excellent detergent properties, particularly as regards solubility and cleaning ability even in hard water. The materials are useful for washing porous materials such as fabrics; surfaces of living organisms, typically the skin and hair of human beings or lower animals; and for washing materials having hard, comparatively impervious, surfaces such as sheet metal or plastics in various forms including but not limited to dishes and silverware. The materials are useful at intermediate temperatures at low temperatures such as 20–30° C., as well as at hot water temperatures, typically 80 to 100° C. or higher, and at atmospheric pressure or higher or lower pressures. Utility under such a wide variety of conditions permits a single composition to be used for most if not all cleaning applications for an entire family or business establishment, for example.

DESCRIPTION OF THE DRAWING

The single figure of the drawing is a ternary diagram showing the properties of various olefin sulfonate compositions. Equal-effectiveness lines for various compositions are shown based on comparison with a standard detergent system. The present invention relates to the compositions in the area A-B-C-D-E-F-G-A of the figure.

DESCRIPTION OF THE PREFERRED EMBODIMENTS

In accordance with the present invention, olefin sulfonates are provided which are based on the saponified products of sulfonation of monoolefin mixtures having from about 12 to about 16 carbon atoms per molecule and averaging from about 14.7 to about 15.9 carbon atoms per molecule. A narrower preferred range is based on the saponified product of the sulfonation of mixtures of monoolefins having mainly 12 and 16 carbon atoms per molecule containing from zero to about 15 wt. percent sulfonates having 14 carbon atoms per molecule. Preferred olefins range from about 60 to about 98 mol percent vinyl, from about 1 to about 30 mol percent vinylidene and from about 1 to about 15 mol percent internal olefins. Olefins sulfonated may include C_{12} , C_{13} , C_{14} , C_{15} , C_{16} or mixtures provided that the mixtures meet the foregoing requirements. Of these, preferred olefins are those containing even numbers of carbon atoms per molecule.

Such olefins are preferably produced by chain growth with ethylene on triethyl aluminum.

In typical preferred olefin mixtures, the C_{12} olefins are from about 90 to about 98 mol percent vinyl and from about 1 to about 7 percent each of vinylidene and internal olefins. The C_{14} olefins are from about 80 to about 90 mol percent vinyl, from about 5 to about 12% each

of vinylidene and internal olefins. The C₁₆ olefins are from about 60 to about 70 mol percent vinyl, from about 20 to about 30% vinylidene and from about 5 to about 15% internal olefins.

When such mixtures of olefins are reacted with SO₃ and saponified with NaOH, for example, the products are principally isomeric spectra of alkene sulfonic acid sodium salts, hydroxy alkane sulfonic acid sodium salts, alkene disulfonic acid disodium salts and hydroxy alkane disulfonic acid disodium salts. Similarly, where the saponification is with caustic potash the products are potassium salts of these acids. These compounds are termed olefin sulfonates. They are exemplified (as sodium salts) by the basic formulas:

where R, R' and R'' are H or alkyl (C_nH_{2n+1}) and where in the total number of carbon atoms in R, R' and R'' is predominantly 7, 9 and 11.

Additional components which may be present in trace amounts include trisulfonates and higher order sulfonates. The ratios of the various sulfonates of these categories normally present on a weight basis in the products of this invention are from about 30 to about 70 percent of alkene sulfonates, from about 20 to about 70 percent of hydroxy alkane sulfonates, from about 2 percent to about 15 percent of the disulfonates, and about 1 percent or less of trisulfonates, etc., such polysulfonates containing approximately equal amounts of alkane and hydroxy alkane compounds.

The foregoing sulfonate compounds are believed to be the result of the formation and cleavage of sultone intermediates. Such sultone intermediates form preferentially as rings with a specific number of atoms per ring, typically 5. Ratings of other numbers of atoms such as 4 and 6 are formed generally in lesser proportions. On hydrolysis the sultones open to provide the alkene sulfonates and hydroxy alkane sulfonates where the location of the unsaturation and hydroxyl groups depend to a large extent upon the number of atoms in the rings of the intermediate sultones. Some further ramification of the distribution of the various forms arises through isomerization. Thus, it is characteristic of the alkane sulfonates that they have predominantly 2-3 unsaturation (30-70 percent) with some 1-2 unsaturation (10-25 percent), some 3-4 unsaturation (5-25 percent), some 4-5 unsaturation (5-10 percent) and so on. Similarly, it is characteristic of the hydroxy alkane sulfonates that they are predominantly 3-hydroxy compounds (about 50-70 percent) with lesser amounts of 2-hydroxy, 4-hydroxy and 5-hydroxy compounds. The disulfonates, trisulfonates may be regarded as the result of the reaction of a second molecule of SO₃ with the double bond of an alkene sulfonate precursor and hence involving further ramifications as several spectra based on the spectra of alkene sulfonates.

It is evident that the hydrocarbon structures of the various compounds exemplified are principally constituted by a ramified substituent containing portion or radical having about 5 carbon atoms connected to a long unsubstituted hydrocarbon radical. In general, the length variation of the unsubstituted radical is small over the range of 12-16 total carbon atoms per molecule, thus it is not essential that the relative proportions of vinyl, vinylidene and internal olefin structures be the same for all starting

olefins or the resultant products. Although such similarity of distributions for the various molecular weights is preferred in some instances, it is preferred in some instances that there be a higher percentage of non-vinyl molecular structures in the C₁₆ starting olefins than in the C₁₄ starting olefins thereby maintaining a greater degree of similarity in the number of carbon atoms in the long unsubstituted hydrocarbon radical.

Examples of typical compounds in the mixtures described herein include the following.

- 5 tetradec-1,2-ene-1-sulfonic acid sodium salt
 hexadec-1,2-ene-1-sulfonic acid potassium salt
 dodec-1,2-ene-1-sulfonic acid sodium salt
 tetradec-2,3-ene-1-sulfonic acid sodium salt
 15 hexadec-2,3-ene-1-sulfonic acid sodium salt
 tetradec-3,4-ene-1-sulfonic acid potassium salt

 salt)
 70 tridec-8-ol-5-(1'-ethyl methylene sulfonic acid sodium
 salt)
 tetradec-4-ol-1,2-disulfonic acid-disodium salt
 hexadec-4-ol-1,2-disulfonic acid-disodium salt
 undec-7-ol-5-sodium sulfonate-5-(1'-ethyl-methylene
 sodium sulfonate)

tridec-7-ol-5-sodium sulfonate-5-(1'-ethyl-methylene sodium sulfonate)
tetradec-5-ol-1,2-disulfonic acid-dipotassium salt

The sulfonate compositions are useful as detergents per se and in combination with other detergent active compounds, builders and adjuvant compounds. These materials are well known in the art.

Other actives useful in conjunction with the present compositions include anionic, nonionic, ampholytic and zwitterionic synthetic detergents individually and in various combination. Typical other actives include alkali metal and ammonium salts of higher fatty acids, alcohol sulfates, linear alkyl sulfonates, alkali metal, alkaline earth metal and ammonium alkaryl sulfonates and fatty alcohol alkoxy sulfates. Typical specific compositions include sodium dodecylbenzenesulfonate, sodium xylene sulfonate, sodium nonylphenol ether sulfate (40 percent ethylene oxide).

Builders are ordinarily used such as water soluble inorganic alkaline builder salts, water soluble organic alkaline builder salts, and mixtures thereof. The proportions of builders to such sulfonate compounds generally range from about 10:1 to about 1:10 by weight, with about 5:1 to about 1:2 being preferred.

Typical builders for use with olefin sulfonates are well known as, for example, set forth in U.S. Pat. 3,332,880. They include ammonium or alkali metal borates, carbonates, and phosphates; ammonia or alkali metal polycarboxylates, alkali metal polyphosphates. Typical builders are sodium tripolyphosphate, tri-sodium nitroacetate, potassium ethane-1-hydroxy-1,1-diphosphate.

The following examples indicate preferred embodiments of the present invention.

EXAMPLE I

A high purity dodecene olefin cut was sulfonated and the product saponified to provide a blending base for washing property tests.

The starting C₁₂ olefins had the following weight percent distribution by carbon atoms per molecule using vapor phase chromatography (VPC). C₁₂ 99+ percent by weight, traces of C₁₀ and C₁₄ olefins and of paraffins of similar boiling points.

The overall distribution (mol percent) of the olefins on a basis of molecular structure as determined by nuclear magnetic resonance (NMR) was as follows:

Vinyl olefins	93.0
Vinyldene olefins	3.7
Internal olefins	3.3
100.0	

The dodecene was reacted in a laboratory falling film sulfonation reactor system similar to that described in Soap and Chemical Specialty 43, 122 (May 1967) using an SO₃ olefin molar feed ratio of 1.04. The reactor was a jacketed tube of 5 mm. internal diameter and 75 cm. length. SO₃ and nitrogen (5 mol percent SO₃) were fed as a gaseous phase at the top. The olefin was also fed at the top and in a liquid phase. The reactor temperature was 38 to 40° C. The olefin feed rate was 24 grams per hour per millimeter of internal periphery of the vertically disposed tubular reactor.

The sulfonation effluent was saponified by reaction at reflux for eight hours with 1-normal NaOH solution fed at 50-60° C. The NaOH was used in about 25 percent excess above the stoichiometric. After saponification, residual oil phase material was removed, then the mixture was cooled and back titrated to neutrality with 1-normal H₂SO₄ to form product olefin sulfonates.

EXAMPLE II

Example I was repeated using a high purity tetradecene cut containing 98.0 weight percent C₁₄ olefins, 1.3 weight

percent C₁₂ olefins and traces of C₁₆ and other olefins and paraffins. The olefin mixture contained an overall distribution (mol percent) on a basis of molecular structure as determined by nuclear magnetic resonance (NMR) as follows:

Vinyl olefins	82.0
Vinyldene olefins	10.9
Internal olefins	7.1
100.0	

The olefins were sulfonated and the product saponified as in Example I, all conditions being the same, with the exception of the olefin feed rate which in this instance was 28 grams per hour per millimeter of internal periphery of the vertically disposed tubular reactor.

EXAMPLE III

Example I was repeated with a high purity hexadecene cut containing 96 percent C₁₆ olefins, 3 percent C₁₄ olefins, the balance being primarily C₁₈ and C₁₂ olefin and traces of paraffins.

The overall distribution (mol percent) on a basis of molecular structure as determined by nuclear magnetic resonance (NMR) was as follows:

Vinyl olefins	63.0
Vinyldene olefins	27.2
Internal olefins	9.8
100.0	

The olefins were sulfonated as in Example I, all conditions being the same, with the exception of the olefin feed rate which in this instance was 32 grams per hour per millimeter of internal periphery of the vertically disposed tubular reactor. The sulfonation product was converted to alkali metal salts as in Example I.

EXAMPLE IV

The sulfonate products of Examples I, II and III were combined in various proportions by weight to provide various sulfonate mixtures for testing for washing performance. Data based on the results are tabulated in the figure. The curves for the various performance percentages from 30 percent to 85 percent inclusive are based upon the results obtained when using the sulfonate products of the Examples I, II and III in the approximate proportions indicated, considering the deoiled sulfonate portion of the product of Example I as all C₁₂, that of Example II as all C₁₄ and that of Example III as all C₁₆. The data for the 90 percent line of the figure is corrected for the actual proportions of the starting olefins, considering olefins lower than C₁₂ as C₁₂ and those higher than C₁₆ as C₁₆. The 90 percent line represents from about 4 to about 33 wt. percent C₁₂ sulfonates, from 0 to about 18 percent C₁₄ sulfonates and from about 60 to about 96 percent C₁₆ sulfonates. The corrected compositions for the points A through G of the 90 percent line of the figure are as follows:

	Wt. percent		
	C ₁₂	C ₁₄	C ₁₆
A	33.2	0	66.8
B	4.1	0	95.9
C	5.7	8.4	85.9
D	11.3	15.8	72.9
E	16.9	17.5	65.6
F	22.4	15.0	62.6
G	27.9	9.4	62.7

The difference between the approximate proportions and the actual proportions is small for the 90 percent performance data and negligible for the 35-85 percent data. The 30-85 percent data is readily converted to an actual basis using the analysis given in Examples I, II and III.

The olefin sulfonate mixtures were tested using a standard comparative Dishwashing Test (J.A.O.C.S. 43, 576 (1966)) to achieve a standard performance evaluation. This testing involves comparison to the performance of a representative standard washing preparation similar to commercial light duty dishwashing concentrates containing 60 percent LAS (linear alkyl benzene sulfonate, Ultrawet K), 30 percent AES (alcohol ethoxy sulfate, Steol 4N) and 10 percent LDEA (lauryl diethanol amide, Ninol AA62 extra). Tests were with water of 50-150 p.p.m. hardness at a temperature of 49° C. using active concentration of 0.045 wt. percent.

The olefin sulfonates (sodium salts) were formulated with a monoethanol amide (Stephen LMMEA) in a ratio of about 4 parts by weight of olefin sulfonates and 1 part of amide.

Results of the test are plotted in the figure, the performance lines indicating percentage based on number of plates washed by the test composition relative to the number of plates similarly washed by the standard composition.

EXAMPLE V

The foregoing experiments are repeated with other sulfonation systems and conditions, including pot type reactors, sprayed chamber reactors, and the like, using saponification under various conditions of temperature and with various arrangements for immediate and delayed neutralization or hydrolysis of the sulfonation effluent as a separate step before complete saponification and using various proportions of caustic or alkaline substance ranging from about stoichiometric (1:1) based on the number of moles of sulfonic acid radicals or precursors present in the sulfonation effluent to about a 50 percent excess of mols of caustic or alkaline substance. Olefins sulfonated include substantially pure olefins with respect to molecular weight as well as carbon skeleton structure, as well as sub combinations, for subsequent blending, and also include total compositions for use without requiring subsequent blending.

We claim:

1. A mixture of water soluble olefin sulfonate salts which results from saponifying the reaction product of SO_3 and olefins having from about 12 to about 16 carbon atoms per molecule, the proportions of C_{12} , C_{14} and C_{16}

olefin sulfonates being within the area defined by the points ABCDEFGA of the figure.

2. The sulfonates of claim 1 further characterized as having from about 12 to about 16 carbon atoms per molecule, averaging from about 14.7 to about 15.9 carbon atoms per molecule, and containing from 0 to about 15 wt. percent of sulfonates having 14 carbon atoms per molecule.

3. The sulfonates of claim 1 further characterized as having from about 4 to about 33 percent C_{12} sulfonates, from 0 to about 18 percent C_{14} sulfonates, and from about 60 to about 96 percent C_{16} sulfonates.

4. The composition in accordance with claim 1 wherein the olefin sulfonate salts are salts of sodium.

5. The composition in accordance with claim 1 wherein the sulfonates are salts of sodium or potassium.

6. The sulfonates of claim 1 further characterized as being derived from mixed olefins containing from about 60 to about 98 mol percent vinyl olefins, from about 1 to about 30 mol percent vinylidene olefins and from about 1 to about 15 mol percent internal olefins.

7. The sulfonates of claim 1 further characterized as being derived from mixed olefins wherein:

(a) the C_{12} olefins are from about 90 to about 98 mol percent vinyl olefins, from about 1 to about 7 percent vinylidene olefins and from about 1 to about 7 percent internal olefins,

(b) the C_{14} olefins are from about 80 to about 90 mol percent vinyl olefins, from about 5 to about 12 percent vinylidene olefins and from about 5 to about 12 percent internal olefins, and

(c) the C_{16} olefins are from about 60 to about 70 mol percent vinyl olefins, from about 20 to about 30 percent vinylidene olefins and from about 5 to about 15 percent internal olefins.
